INVENTOR.
Sebastian Keller

United States Patent Office.

SEBASTIAN KELLER, OF ELIZABETHTOWN, PENNSYLVANIA.

Letters Patent No. 75,551, dated March 17, 1868.

IMPROVEMENT IN PORTABLE FENCE.

The Schedule referred to in these Letters Patent and making part of the same.

TO ALL WHOM IT MAY CONCERN:

Be it known that I, SEBASTIAN KELLER, of Elizabethtown, in the county of Lancaster, in the State of Pennsylvania, have invented a new and improved Mode of Constructing Portable Fencing; and I do hereby declare that the following is a full and exact description thereof, reference being had to the accompanying drawings, and to the letters of reference marked thereon.

The nature of my invention consists in the mode of constructing portable fencing, by means of a stake passing through between the first and second rails from the top, secured by a key passing through the stake, and bracing the panels together, as shown in Figure A of the annexed drawing.

To enable others skilled in the art to make and use my invention, I will proceed to describe its construction.

Figure A shows an end view of the fence in a finished state, except that the uprights are not shown.

Figure B shows a front view.

C is the stake, with key shown in its place; D, small peg to protect the fence from being raised by hogs, &c., &c. E E are corner panels, one of which is like the rest of the fence, except the slots 3 3; the other, same, except one end upright is at an angle with the slope of the fence, and the top and bottom rails only are extended, being notched, 4 4, to match 3 3.

In making the fence, it will be necessary to regulate the space between the first and second rails from the top, according to the thickness of the stakes to be used, (which is not particular, if desired to drive them in the ground, to give more strength to the fence, which would be well enough, at least, every third or fourth panel,) and also according to the slope of the fence and stake desired.

The hole to receive the key 2 should be straight through the stake C, at 1 2. It will be seen at figs. A and B, at 5 6, that all the rails lap over their corresponding rails on same side, except the lower one, which laps on the opposite side, binding the whole structure together.

In sections of country where severe storms are prevalent, or in cases above referred to, the peg D can be used to advantage, but is only required, in such cases, to be applied as shown at 7 8, permitting the head to rest against the upright that secures the outside lower rail. Where the ground is very hilly, it will only be necessary to lap the panels over just enough to receive the stake between the rails, as before described.

It will be seen that the advantages gained in this fence over others are, first, it can be put up and taken down with but little labor; second, that it is in a straight line, not requiring so much room as a zigzag; the boards are nailed about five or six inches from the end, and not liable to split; third, that it slopes on either side, which protects it from the wind and from cattle rubbing against it; fourth, it is simple, and can be made cheaply, which enables every farmer to be his own fence-maker.

What I claim as my invention, and desire to secure by Letters Patent, is—

The mode of supporting portable fencing as herein described.

SEBASTIAN KELLER.
